W. S. MOODY

ELECTRICAL APPARATUS

Filed Nov. 4, 1925

Inventor:
 Walter S. Moody,
 by *Alfred S. Lunt*,
 His Attorney.

UNITED STATES PATENT OFFICE.

WALTER S. MOODY, OF PITTSFIELD, MASSACHUSETTS, ASSIGNOR TO GENERAL ELECTRIC COMPANY, A CORPORATION OF NEW YORK.

ELECTRICAL APPARATUS.

Application filed November 4, 1925. Serial No. 66,839.

My invention relates to electrical apparatus and more particularly to the encased oil immersed type of electrical apparatus such as a transformer having a winding with 5 taps connected to a switch for changing the tap connections. It is desirable that the switch be close to the apparatus so that the leads to the winding taps may be short and to this end it has been customary to locate 10 the switch inside the casing and immersed in the oil with the apparatus. A switch so located, however, is more or less inaccessible for inspection or repair and it is not always convenient to locate the switch inside the apparatus casing with proper mechanical and electrical clearances without increasing the size of the casing, particularly in connection with apparatus operating at very high voltages. When the switch is located in the 20 same body of oil with the apparatus too, it cannot be safely operated while carrying current because arcing at the switch contacts will affect the insulating qualities of the oil. The general object of the invention is to provide an improved arrangement in which the 25 switch is readily accessible, in which the tap leads are reasonably short and in which both the switch and the tap leads are electrically and mechanically well protected. Another object of the invention is to provide 30 an improved arrangement whereby the switch may be operated if desired while carrying current without danger of affecting the insulating qualities of the oil in which 35 the apparatus is immersed.

Other objects and advantages will appear from the following description taken in connection with the accompanying drawing in which Fig. 1 is a view, partly in section, of 40 an encased oil immersed transformer with a tap switch arranged in accordance with the invention, and Fig. 2 is a circuit diagram of the tap switch with its connections to one of the transformer windings.

Like reference characters indicate similar 45 parts in both figures of the drawing.

The invention is illustrated in the drawing in connection with a transformer 10 immersed in a body of insulating oil within a 50 casing 11. This casing 11 is completely filled with oil at all times, an expansion chamber 12 being provided to permit expansion and contraction of the oil due to changes in its temperature. A tap changing

switch 13 is connected by tap leads 14 to one 55 of the windings 15 of the transformer so that the number of effective turns in this winding may be changed as desired by changing the position of the movable contactor of the switch. 60

The switch 13 is enclosed in a casing 16 supported by a hollow bracket 17 secured to the side of the transformer casing 11 near the winding 15 to which it is connected by the leads 14. These tap leads extend from 65 the switch 13 to the winding 15 through the hollow bracket 17 and through an opening in the transformer casing 11 at the point where the bracket is attached so that the leads are completely protected and reasonably short. The switch casing 16 and the passageway through the bracket 17 are filled with oil for insulating purposes. An important advantage of this construction is 70 that the necessity for insulating bushings is 75 avoided where the tap leads 14 pass through the wall of the transformer casing.

In some cases, it may be desirable to operate the switch 13 while the transformer is under load and the switch is carrying current. To permit this to be done without affecting the insulating qualities of the oil surrounding the transformer, a barrier or seal 18 is provided in the passageway between the switch casing 16 and the transformer casing 11 to prevent interchange of oil between the two casings. Arcing at the 80 switch contacts may affect the oil in the switch casing 16 but this oil is prevented by the seal 18 from entering the transformer 85 casing 11.

The switch casing 16 should be oil tight to prevent leakage. It is not necessary, however, that the seal 18 be absolutely oil tight as the oil pressures on its opposite 90 sides are equal and any simple form of seal which will prevent appreciable passage of oil from the switch casing to the transformer casing will be satisfactory. The switch casing 16 is removable to permit 100 inspection and repair of the switch. While this casing 16 is open, there may be a small leakage of oil from the transformer casing past the seal 18 but this is not objectionable. The operating shaft 19 of the 105 switch is preferably extended through an oil tight stuffing box for convenient operation of the switch at any time.

What I claim as new and desire to secure by Letters Patent of the United States is:—

1. The combination with electrical apparatus having a winding, of a tap switch, a casing enclosing said apparatus, a separate casing enclosing said tap switch, said two casings containing insulating oil in which said apparatus and tap switch are immersed, there being a passageway between said two casings, said passageway entering the side of said apparatus casing near said apparatus, tap leads extending through said passageway from said tap switch to the winding of said apparatus, said passageway containing insulating oil surrounding said tap leads, and a seal to prevent interchange of oil between said two casings through said passageway.
- 10 2. The combination with electrical ap-

paratus having a winding, of a tap switch, a casing enclosing said apparatus, a separate casing enclosing said tap switch, said two casings containing insulating oil in which said apparatus and tap switch are immersed, there being a passageway between said two casings, said passageway entering the side of said apparatus casing near said apparatus, tap leads extending through said passageway from said tap switch to the winding of said apparatus, said passageway containing insulating oil surrounding said tap leads, said tap switch casing being oil tight to prevent leakage of oil, and a seal to prevent interchange of oil between said two casings through said passageway.

In witness whereof I have hereunto set my hand this 2nd day of Nov. 1925.

WALTER S. MOODY.
